UNITED STATES PATENT OFFICE.

JOHN JOHNSON, OF SALT LAKE CITY, UTAH.

AXLE-SPINDLE-TURNING MACHINE.

No. 857,242.

Specification of Letters Patent.

Patented June 18, 1907.

Application filed May 3, 1906. Serial No. 315,113.

To all whom it may concern:

Be it known that I, JOHN JOHNSON, a citizen of the United States, residing at Salt Lake City, in the county of Salt Lake and State of Utah, have invented certain new and useful Improvements in Axle-Spindle-Turning Machines; and I do declare the following to be a full, clear, and exact description of the invention, such as will enable others skilled in the art to which it appertains to make and use the same.

My invention relates to improvements in machines for turning the spindles of vehicle axles and for doing similar work.

One object of the invention is to provide a simple and practical portable machine by means of which the axle spindles of buggies and other vehicles may be turned down when worn, and their original taper maintained.

With the above and other objects in view, the invention consists in certain novel features of construction, combination and arrangement of parts hereinafter described and claimed.

In the accompanying drawings,—Figure 1 is a perspective view showing my improved machine; applied to a vehicle axle and its spindle; Fig. 2 is a top plan view of the machine; Fig. 3 is a vertical longitudinal sectional view; Fig. 4 is an elevation of the outer end of the machine; Figs. 5 and 6 are vertical transverse sectional views, taken respectively on the planes indicated by the lines 5—5 and 6—6 in Fig. 3; and Fig. 7 is a detail view of the sectional nut by means of which the cutter carrier is connected to the feed screw.

Referring more particularly to the drawings, A denotes the axle of a buggy or other vehicle, which has the usual longitudinally-tapered spindle S provided at its inner end with a collar C and at its outer ends with a reduced screw-threaded end E, and the numeral 1 denotes my improved portable machine for turning the spindle and maintaining its taper. This machine comprises a collar 2 adapted to be removably clamped upon the axle A by means of set screws 3, which space it from and center it upon said axle. Said collar is of cylindrical form and has at its outer end an annular flange 4 and at a suitable point adjacent to its inner end a projecting stud 5 formed with a threaded-opening to receive a screw 6, which is adapted to serve as a trip. Removably mounted upon the sleeve or collar 2 is a rotatable frame or carriage 7 consisting of inner and outer

heads or end members 8, 9, connected by guide rods 10. These heads or end members 8, 9, are preferably in the form of castings, the inner one 8 having a central opening of greater diameter than the collar or sleeve 2 and its flange 4 and being removably retained upon said parts by a substantially U-shaped washer or key 11, which is inserted between said flange and the adjacent face of 65 the head 8, as clearly shown in Figs. 2 and 5 of the drawings.

The heads 8, 9, are formed adjacent to their ends with openings through which the cylindrical guide rods 10 project, and in 70 which they slide, so that by means of set screws 12, said heads may be adjusted toward and from each other and secured in an adjusted position.

Slidable longitudinally of the frame or carriage 7 is a cutter carrier 14, also preferably in the form of a casting, and having at its center a large opening, through which the spindle extends. Said carrier has at diametrically opposite points projecting lugs 80 15, which are bored to permit the guide rods 10 to slide freely therethrough, and one of the lugs 15 is also formed with an opening, through which the longitudinally-extending feed screw 16 extends. Said carrier is further provided with arms 15^a which are at right angles to the lugs 15. Said screw is provided for the purpose of feeding the cutter carrier 14 longitudinally upon the frame or carriage 7, and has its ends mounted to 90 turn in the heads 8, 9. Upon the outer end of said screw is provided a hand-wheel 17, and upon its inner end is secured a five-pointed star-shaped wheel 18, which is so disposed that one of its points engages the 95 screw 6 upon each rotation of the frame or carriage 7 to partly turn said feed screw. The lug or projection 15 is slotted or bifurcated to receive a sectional nut which engages the threads of the feed-screw 16 when 100 it is desired to cause the latter to feed the carrier 14 longitudinally upon the frame 7, and which is disengaged from the same when it is desired to quickly shift the carrier in either direction upon said frame. This sectional 105 nut preferably consists of two members 19, 20, each of which is in the form of a ring or an annular band 21 having a half nut 22 projecting from it. These members or sections 19, 20 are adapted to fit in the space formed by 110 slotting or bifurcating the projecting lug 15, and the adjacent guide rod 10 projects

- through alining openings in their ring portions 21, so that they swing upon said rod 10 to permit their opposing half nut portions 22 to be moved into and out of engagement with 5 the threads of the feed screw 16. In order to detachably secure said nut sections together and in engagement with the feed-screw, I provide a screw 23 upon their nut portions 22, as clearly shown in the drawings.
- 10 Each arm 15^a of the cutter carrier 14 has projecting from it one or more lugs 24, which are grooved to receive cutting tools 26. The latter are retained in said grooves by straps 27 secured upon said lugs and they are ad- 15 justed or fed inwardly by means of screws 28, provided in threaded ears upon said lugs and having their inner ends engaged with the outer ends of the cutters 26. One of the arms 15^a has its outer face grooved to receive 20 a crank-handle 29, by means of which the frame or carriage 7, and hence the cutters, are rotated. This handle is preferably ad- justably secured in its groove by means of a 25 screw 30 carried by said crank handle, and it may be of any desired form and construc- tion.

The outer end of the frame or carriage 7 is supported by an end pin 31, which extends through an opening 32 in the outer head 9 of 30 the frame or carriage, and has its pointed inner end seated in a centrally-disposed recess or seat in the outer end of the threaded portion E of the spindle S. This end pin 31 serves as a pivot and support for the outer 35 end of the frame and it is adjustably secured in the opening 32 by means of a set screw 33.

In order to maintain the usual taper upon the spindles of buggy or other vehicle axles that are turned by the machine, the hole 32 40 is not bored in exact longitudinal alinement with the axis of the remaining portion of the machine, but slightly eccentric or off said axis, as shown in the drawings. In practice, I preferably bore the opening 32 one-six- 45 teenth of an inch higher or nearer the side of the frame or carriage 7 from which the handle projects, while the opening in the head 8 is bored concentrically, so that the cutters 26 will be fed by the screw 16 in a longitudinally- 50 inclined path to produce a taper of about one-eighth of an inch upon the spindle S, this being the customary taper for buggy spindles. It will be understood that this eccentricity of the opening 32 will be such as is 55 required by the desired taper of the spindle, and that when said opening 32 is concentric or in longitudinal alinement with the central axis of the machine, the spindle or other object cut by the tools 26 will be turned to a 60 true cylindrical form.

In using the machine, the collar or sleeve 2 is first centered and clamped upon the axle, and the frame or carriage 7 is then applied to the spindle and secured upon the outer end 65 of said collar by means of the U-shaped

washer or key, as previously stated, and as shown in Fig. 1. The latch 23 is then operated to release the members of the sectional nut from the feed screw, and the cutter carrier moved outwardly to the outer end of the 70 spindle. The members of the sectional nut are then swung together and upon the feed screw and secured by the latch, and the cutters 26 are then adjusted so that they will cut the spindle the desired depth. The handle 75 29 is then turned to rotate the frame or carriage 7 and cause the cutters to cut the spindle. Upon each rotation of the frame 7, the trip or pin 6 will engage one of the points of the wheel 18 and give the feed screw a par- 80 tial rotation, so that the carrier 14 will be fed from end to end of the spindle. When the cutters reach the collar C of the spindle, they are then adjusted so that the collar is cut to the same extent as the spindle. 85

It will be seen that by disengaging the members of the sectional nut from the feed screw and temporarily dispensing with the use of the same, and by substituting a head having its opening 32 with its center lying in 90 a common plane with the center of the guide rods 10 and by using suitable tools instead of the cutters 26 I am able to cut the threads E on the outer end of the spindle, in this operation one dull cutter being used to make the 95 feed by following in the old or worn threads, and another cutter being provided for doing the recutting of the threads.

From the foregoing description, taken in connection with the accompanying drawings, 100 the construction and operation of the invention will be readily understood, without requiring a more extended explanation.

While I have shown and described the preferred embodiment of my invention, it will 105 be understood that I do not wish to be limited to the exact showing herein set forth, since various changes in the form, proportion and the minor details of construction may be resorted to without departing from 110 the principle or sacrificing any of the advantages of this invention, as defined by the appended claims.

Having thus described my invention, what I claim as new, and desire to secure by Letters-Patent, is,— 115

The herein-described axle spindle turning machine comprising a collar having means for centering and securing the same on an axle and provided with a radially extending arm having a trip projecting therefrom, a frame comprising outer and inner heads and guide rods connecting them, said outer head having a pivot pin to engage the outer end of the axle spindle and support the outer end of 120 the frame for revolution, and said inner head being detachably and revolvably mounted on the collar, a carriage having lugs slidably mounted on the guide rods and radial arms at an angle to said lugs, said arms having 125 130

guide devices and lugs beyond the outer ends of such guide devices and one of said arms also having a lever whereby such carriage together with the frame may be revolved around the axle spindle, cutters movable radially in the guide devices of the said arms of said carriage, adjusting screws for said cutters operating in threaded openings in the said lugs of said arms, a feed screw mounted in and connecting the heads and provided at its inner end with a star wheel for coaction

with the trip to rotate said feed screw by a step-by-step movement when the frame is revolved, and a nut secured to the carriage and engaged by the feed screw.

15

In testimony whereof I have hereunto set my hand in presence of two subscribing witnesses.

JOHN JOHNSON.
